UNITED STATES PATENT OFFICE

CHARLES F. SIMMS, OF CONCORD, NEW HAMPSHIRE, ASSIGNOR TO CONCORD SILVER-SMITHS, INC., OF CONCORD, NEW HAMPSHIRE, A CORPORATION OF NEW HAMPSHIRE

DESIGN FOR A SPOON OR SIMILAR ARTICLE

Application filed October 26, 1931. Serial No. 41,521. Term of patent 14 years.

To all whom it may concern:

Be it known that I, CHARLES F. SIMMS, a citizen of the United States, residing in Concord, in the county of Merrimack and State of New Hampshire, have invented a new, original, and ornamental Design for a Spoon or Similar Article, of which the following is a specification, reference being had to the accompanying drawings, forming a part thereof.

Figure 1 is a front elevation of a spoon showing my new design.

Figure 2 is a back view.

Figures 3, 4, 5 and 6 are cross sectional views on the correspondingly numbered section lines of Figures 1 and 2.

I claim:

The ornamental design for a spoon or similar article, substantially as shown.
